UNITED STATES PATENT OFFICE.

PETER C. MCCHESNEY, OF MILLBURN, NEW JERSEY.

IMPROVEMENT IN POCKET TOOTH-BRUSHES.

Specification forming part of Letters Patent No **174,832**, dated March 14, 1876; application filed November 21, 1874.

To all whom it may concern:

Be it known that I, P. C. MCCHESNEY, of Millburn, Essex county, New Jersey, have invented an Improved Pocket Tooth-Brush, of which the following is a specification:

My invention relates to that class of portable tooth-brushes in which the stem carrying the brush may be detached from and placed in a hollow handle; and my invention consists in constructing the brush as fully described hereafter, to insure greater strength and facilitate the adjustment of the parts.

In the accompanying drawing, Figure 1 is a longitudinal view, partly in section, showing the brush ready for use; and Fig. 2, a longitudinal view, partly in section, showing the brush arranged for transportation.

The case B, which constitutes the handle, is hollow and open at one end, in which is a slot, e, and in the closed end is a threaded opening or socket, s, for the reception of a threaded metal pin, I, projecting from a block, G, upon the end of the stem A. The stem carries the usual brush, and, with the latter, is of such a size as to be readily contained within the hollow handle B, and when in-

serted, as shown in Fig. 2, a shoulder, x, on the block G, bearing against the side of the case, prevents the stem from falling, pressing the brush against the case and bending the bristles. A lug, J, on the block G, projecting through the slot e, not only prevents the stem from turning, but also affords a means of readily withdrawing the stem by pressing with the finger upon the projecting end of the lug. The threaded pin I being of metal insures a more durable and stronger joint than the ordinary screw-connections made by threading a projecting portion of the stem.

I do not claim, broadly, a tooth-brush having a detachable stem adapted to a hollow handle; but

I claim—

The hollow handle or case B, its threaded opening s, and slot e, in combination with the brush-stem A, screw I, and projection J, all constructed and arranged substantially as set forth.

PETER C. MCCHESNEY.
